UNITED STATES PATENT OFFICE.

CHARLES M. MARKHAM, OF MILWAUKEE, WISCONSIN.

JACK-ACTUATING LEVER.

1,401,172.

Specification of Letters Patent. Patented Dec. 27, 1921.

Application filed November 15, 1919. Serial No. 338,408.

To all whom it may concern:

Be it known that I, CHARLES M. MARKHAM, a citizen of the United States, and resident of Milwaukee, in the county of Milwaukee and State of Wisconsin, have invented new and useful Improvements in Jack-Actuating Levers, of which the following is a description, reference being had to the accompanying drawings, which are a part of this specification.

This invention relates to improvements in jack actuating levers more particularly adapted for concrete work.

In the construction of modern concrete work lifting jacks are utilized for raising and holding the forms or false work which supports the concrete before it has set, and detachable means are preferably used for actuating the raising portion of the jack.

It is one of the objects of the present invention to provide a lever construction for raising the movable portion of lifting jacks which may be easily attached or detached from the jack without the use of tools of any kind, and which when attached will firmly engage the parts and permit the raising of the lifting member with a minimum effort.

A further object of the invention is to provide a jack actuating lever with a clamping means which is moved into clamping engagement with the lifting member of the jack each time the lever is moved upwardly.

A further object of the invention is to provide a jack actuating lever having a toothed clamping member which is moved horizontally into clamping engagement with the lifting member of the jack with a plurality of the teeth engaging the lifting member each time the lever is moved upwardly.

A further object of the invention is to provide a jack actuating lever having a toggle link connection between the actuating lever and the clamping means to form a more efficient power leverage.

A further object of the invention is to provide a jack actuating lever which is of simple construction, is strong and durable and is well adapted for the purpose described.

With the above and other objects in view, the invention consists of the improved jack actuating lever and its parts and combinations as set forth in the claims and all equivalents thereof.

In the accompanying drawing in which

the same reference characters indicate the same parts in all of the views:

Figure 1 is a side view of a lifting jack showing the improved actuating lever attached thereto;

Fig. 2 is a top view of the actuating lever on a larger scale;

Fig. 3 is a side view of the actuating lever, a part broken away; and

Fig. 4 is a detail sectional view, on a larger scale, taken on line 4-4 of Fig. 2.

Referring to the drawing the numeral 8 indicates a standard, 9 the telescoping lifting member thereof and 10, one of the clamping jaws of a lifting jack which the improved actuating lever designated as a whole by the reference character 11 is used in connection with. The jack is formed with opposite shouldered flanges 12 for supporting a portion of the actuating lever 11 thereon.

The actuating lever comprises a lever member 13, a clamping collar 14, a slidably toothed jaw 15 and a toggle link connection 16 connecting the lever member 13 to the collar 14 and the jaw 15. The clamping collar 14 is of semicircular shape to slip freely sidewise over the tubular lifting member 9 and is formed at one end with an enlargement having a transversely extending opening 14' of right angular form in vertical section for holding the slidably clamping jaw 15 mounted therein. The inner end of the clamping jaw is curved to conform to the shape of the portion of the lifting member 9 engaged and is also threaded to form clamping teeth 17 which bite into the lifting member and firmly clamps the collar to the said member. The clamping jaw 15 is moved into and out of engagement with the lifting member by the upper curved link 18, the upper portion of which extends through an opening 19 in the lower portion of the collar and is connected to the collar by a pin 20 to form a pivotal connection therebetween. The short portion 18' of the upper link above the pivot pin 20 forms the short arm of the lever link and extends loosely into an opening 21 in the clamping jaw and reciprocates the said jaw into and out of engagement with the lifting member of the jack each time the link is actuated. The lower link members 22 connecting the lower end of the upper link 18 to the hand or operating lever 13 are pivotally connected at 110

20 to 25 30 35 40 45 50 55 60 65 70 75 80 85 90 95 100 105 110

their lower ends to said hand lever close to the inner or jack engaging end 13' thereof. Said inner end 13' is provided with a notch or recess 23 to form a more firm engagement with the shouldered flanges 12 of the jack upon which it rests when in use.

In operation, the actuating lever is connected to the jack in the manner shown in Fig. 1 and the hand lever is then swung upwardly and downwardly. Each upward swing will at first move the toothed jaw into clamping engagement with lifting member of the jack and afterward lift said member, and each downward movement of the hand lever will at first disengage the jaw from the member and a further downward movement will permit the clamping collar to drop and to be in position to again clamp and move the member upwardly when the hand lever is again raised.

To remove the actuating lever from the jack, it is only necessary to drop the hand lever to its lower position and move the clamping collar laterally from engagement with the lifting member of the jack.

From the foregoing description, it will be seen that the jack actuating lever is of very simple construction, is strong and durable and is well adapted for the purpose described.

What I claim as my invention is:

1. A jack actuating lever, comprising a collar adapted to be temporarily associated with the member to be lifted, a clamping jaw carried thereby, a lever, and a linked connection between the lever and the collar for moving the jaw and the collar into effective lifting engagement with said member.

2. A jack actuating lever, comprising a collar adapted to be temporarily associated with the member to be lifted, a clamping jaw movably carried thereby, a lever having one end portion adjacent the collar, and a link connection between said adjacent end of the lever and the collar for moving said jaw and collar into effective lifting engagement with said member.

3. A jack actuating lever, comprising a collar adapted to be temporarily associated with the member to be lifted, a clamping jaw movably carried thereby, a lever having one end portion adjacent the collar, and a link connection between said adjacent end of the lever and the collar and the jaw for moving the jaw in one direction and the collar in another into effective lifting engagement with said member.

4. A jack actuating lever, comprising a collar adapted to be temporarily associated with the member to be lifted, a clamping jaw

movably carried thereby and having an opening, a lever having one end portion adjacent the collar, a lower link member connected at its lower end to the adjacent lever end, and an upper link member pivotally connected at its lower end to the upper end of the lower link member, the upper end portion of the upper link member engaging the collar and the clamping jaw and moving said parts in different directions.

5. A jack actuating lever, comprising a collar adapted to be temporarily associated with the member to be lifted, a clamping jaw movably carried thereby and having an opening, a lever having one end portion adjacent the collar, a lower link member connected at its lower end to the adjacent lever end, and an upper link member pivotally connected at its lower end to the upper end of the lower link member, the upper end portion of the upper link member pivotally connected to the collar and extending through a portion thereof and into the opening of the clamping jaw and moving said parts in different directions.

6. A jack actuating lever, comprising a collar member having a side opening and a bottom opening, a clamping jaw movably carried thereby and having an opening, a lever member having one end portion adjacent the collar, a lower link member pivoted at its lower end to the lever near its adjacent end, and an upper link member pivoted at its lower end to the upper end of the lower link member, the upper link member medially of its length extending through the bottom opening of the collar and pivotally connected thereto and having its upper end portion extending into the opening in the jaw member.

7. A jack actuating lever, comprising a semicircular member having a bottom opening and a transversely extending clamping jaw opening, a clamping jaw movably positioned in said last mentioned opening and having a plurality of teeth formed on its clamping face, a lever member having one end portion adjacent the collar and provided with a jack engaging notch, a lower link member pivoted at its lower end to the lever near its adjacent end and extending upwardly therefrom, and an upper link member pivoted at its lower end to the upper end of the lower link member, the upper link member medially of its length extending through the bottom opening of the collar and pivotally connected thereto and having its upper end portion extending into the opening in the jaw member.

In testimony whereof I affix my signature.
CHARLES M. MARKHAM.
